(57) **CLAIM**

The ornamental design for the theft deterrent strap, as shown and described.

DESCRIPTION

FIG. 1 is a perspective view of a first embodiment of the theft deterrent strap showing my new design.

FIG. 2 is a top plan view of FIG. 1.

FIG. 3 is a bottom plan view of FIG. 1.

FIG. 4 is a front elevation view of FIG. 1.

FIG. 5 is a rear elevation view of FIG. 1.

FIG. 6 is a right side elevation view of FIG. 1.

FIG. 7 is a left side elevation view of FIG. 1.

FIG. 8 is a perspective view of a second embodiment of the theft deterrent strap showing my new design.

FIG. 9 is a top plan view of FIG. 8.

FIG. 10 is a bottom plan view of FIG. 8.

FIG. 11 is a front elevation view of FIG. 8.

FIG. 12 is a rear elevation view of FIG. 8.

FIG. 13 is a right side elevation view of FIG. 8.

FIG. 14 is a left side elevation view of FIG. 8.

FIG. 15 is a perspective view of a third embodiment of the theft deterrent strap showing my new design.

FIG. 16 is a top plan view of FIG. 15.

FIG. 17 is a bottom plan view of FIG. 15.

FIG. 18 is a front elevation view of FIG. 15.

FIG. 19 is a rear elevation view of FIG. 15.

FIG. 20 is a right side elevation view of FIG. 15; and,

FIG. 21 is a left side elevation view of FIG. 15.
